Primary Examiner — Michelle E. Wilson*Assistant Examiner* — Clese Moore, Jr.(74) *Attorney, Agent, or Firm* — Dicke, Billig & Czaja, PLLC(57) **CLAIM**

The ornamental design for a motorcycle saddlebag filler panel light housing, as shown and described.

DESCRIPTION

FIG. 1 is a perspective view of the saddlebag filler panel light housing.

FIG. 2 is a front elevation view thereof.

FIG. 3 is a rear elevation view thereof.

FIG. 4 is a top side view thereof.

FIG. 5 is a bottom side view thereof.

FIG. 6 is a first side view thereof; and,

FIG. 7 is a second side view thereof, opposite the first side view.

The features within the housing and the rear surface shown in broken lines form no part of the claimed design.
